UNITED STATES PATENT OFFICE.

HENRY ROSENDAL DAM, OF BROOKLYN, NEW YORK, ASSIGNOR TO INTERSTATE ELECTRIC NOVELTY COMPANY, OF BROOKLYN, NEW YORK, A CORPORATION OF NEW YORK.

DRY CELL.

1,407,386.

Specification of Letters Patent. Patented Feb. 21, 1922.

Application filed June 21, 1920. Serial No. 390,306.

To all whom it may concern:

Be it known that I, HENRY ROSENDAL DAM, a subject of the King of Denmark, residing in the borough of Brooklyn, county 5 of Kings, city and State of New York, have invented certain new and useful Improvements in Dry Cells, of which the following is a specification.

This invention relates to improvements in 10 dry cells of the type where the electrolyte is initially kept inactive in an auxiliary container until the cells are to be put into use, so that no portion of their normal life will be wasted.

15 The invention is particularly applicable to a cell provided with an outer tubular zinc anode and having an inner bobbin cathode consisting of a carbon electrode embedded in a depolarizing mass.

20 One object of this invention is to so construct a dry cell that the electrodes while inactive will be separated from one another, by impervious material. Another object is to construct a cell in such a manner the 25 parts can not be jammed into a position from which it would be difficult to remove them when it is desired to put the cells into action.

20 This and other objects of this invention are set forth in the following description and illustrated in the accompanying drawing in which:

30 Figure 1 is a sectional view of one embodiment of this invention showing a cell 35 with the parts in their original inoperative positions.

Figure 2 is a view illustrating the general form of the auxiliary container.

40 Figure 3 is a sectional view taken on the line 3—3 of Figure 2.

Referring to the drawings, the carbon electrode 10, or cathode is embedded in the depolarizing mass 11, the latter being secured in place by a cloth container or the 45 like. The carbon electrode, the depolarizing mass and the cloth container will be herein-after referred to as the bobbin. Spaced from the bobbin and secured thereto by the wax seal 14, which serves also as an abutment 50 is the insulating tube 13, which extends the full length of the bobbin. Upon the lower face of the seal 14, or abutment, there is preferably disposed a washer 15 formed of non-conductive impervious ma-

terial, such as paraffined cardboard, or the like.

The other electrode of the cell comprises a cylindrical zinc cup 16 or anode open at the top and which is adapted to fit inside the insulating tube 13 and to be telescoped 60 with the same, the bottom of the zinc cup 16 serving as an abutment.

Separating and isolating the zinc cup 16 from the bobbin and enveloping the latter is the waterproof fibrous spacing cup 17 65 which is adapted to co-operate with the wax seal 14, or abutment, and the bottom of the cup 16, the bottom of the cup functioning also as an abutment. The spacing cup 17 is preferably formed of non-conductive 70 impervious material such as paraffined cardboard or the like. The length of the spacing cup 17 is greater than that of either of the zinc cup 16 or the insulating tube 13, so that when the spacing member is in position, the upward telescoping movement of 75 the zinc cup 16 with respect to the bobbin and tube 13 will be limited, and the bottom of the zinc cup will be initially maintained projecting and will be readily accessible for 80 convenient manipulation. By means of this construction the zinc cup 16 cannot be forced into a position from which it would be difficult to grasp it for removal, or where it might injure the bobbin, since the bottom of 85 the cup projects below the lower edge of the insulating tube. The impervious cup 17 initially surrounds the bobbin 10 and prevents moisture salts and other chemicals which may be initially contained in the depolariz- 90 ing mass from escaping therefrom and injuring the zinc cup 16.

Moreover the cup may also serve to accurately centre the bobbin within the surrounding sleeve 13 during the manufacture 95 of the cell, as for example while the wax seal 14 is being applied.

While I have shown a spacing and isolating member consisting of the cup 17 closed at the bottom I may also employ a strip of 100 impervious material rolled around the bobbin in form of a cylinder with overlapping edges and I may close the bottom with a washer. I prefer however to employ impervious spacing cup 17. If desired, a cover 105 21 of cardboard or other suitable material may be employed to protect the exposed lower end of the zinc cup. This cover 21

may be discarded after the battery has been put into operation. However, it is not an essential feature and may be entirely omitted.

5 The paste 18 for activating the cell is initially contained in the auxiliary container 19, as shown in Figures 2 and 3. This container 19 may be of any convenient construction but the preferred form comprises 10 a cylindrical tube of thin celluloid flattened at one end. The paste container 19 is preferably permanently closed at its cylindrical end, and temporarily sealed at its flattened end by folding the tube, as shown at 20 in 15 Figure 2.

When it is desired to prepare the cell for use, the zinc cup 16 is removed from the tube 13 and the spacing cup 17 is removed. To activate the cell, the paste 18 is then 20 squeezed from its celluloid container 19 into the bottom of the zinc cup. The bobbin and the cup 16 are then telescoped into operative position, forcing the paste up between the two electrodes. In this operation, the zinc 25 cup 16 is forced up until its bottom is flush with the bottom of the insulating tube 13, so that when fully assembled the cylindrical portion of the zinc cup is entirely surrounded by the insulating tube.

30 In carrying out this invention it is to be understood that it is not to be limited by the example herein disclosed but may be practiced in various other ways within its general scope.

35 Having thus described my invention what I claim is:

1. A dry cell comprising a telescoping covering member, an electrode, a telescoping electrode surrounding the first named 40 electrode and adapted to slide within said covering member, and a spacing element located within said telescoping electrode and having its opposite ends contacting with said telescoping covering and with said telescoping electrode to retain the telescoping electrode in an extended relation with respect to said telescoping covering.

50 2. A dry cell comprising a telescoping covering member having a closure, an electrode, a telescoping electrode surrounding the first named electrode and adapted to slide within said covering, the telescoping

electrode being provided with a closure, and a spacing element arranged within the second named electrode and normally contacting with said closures, whereby the second named electrode is retained in an extended relation with respect to said covering member. 55

3. A dry cell comprising a tubular telescoping covering member, having a closure, a bobbin connected with said closure, a telescoping electrode surrounding the bobbin and adapted to slide within said covering member, and a cylindrical spacing member 60 located within said telescoping electrode, the spacing member having one end abutting said closure and its opposite end abutting a portion of said telescoping electrode, whereby the telescoping electrode is retained 65 in an extended position with respect to said covering member. 70

4. A dry cell comprising a covering member, an abutment carried by the covering member, a bobbin, a telescoping electrode 75 surrounding said bobbin and adapted to slide within said covering member, said electrode being provided with an abutment, and a spacing member arranged within said electrode and having its ends co-operating 80 with said abutting members, whereby said telescoping electrode is retained in an extended relation with respect to said covering member.

5. A dry cell comprising a tubular covering member, a cup-shaped electrode arranged within said covering member and adapted to slide therein, said cup-shaped electrode being provided with a bottom, 85 a closure for said covering member, a bobbin arranged within said cup-shaped electrode and spaced from the cup-shaped electrode, and a spacing element disposed 90 within the space afforded between the bobbin and the cup-shaped electrode, the spacing element co-operating with said closure and the bottom of the cup-shaped electrode 95 to retain the cup-shaped electrode in an extended relation with respect to said covering member. 100

In testimony whereof, I have affixed my signature to this specification.

HENRY ROSENDAL DAM.
